UNITED STATES PATENT OFFICE

GUSTAV TER MEER, OF MUNICH, GERMANY, ASSIGNOR TO ALBERT T. OTTO & SONS, OF NEW YORK, N. Y., A CORPORATION OF NEW YORK

CENTRIFUGAL SEPARATOR

Application filed February 11, 1930, Serial No. 427,446, and in Germany February 13, 1929.

This invention is an improvement in centrifugal machines of the type in which liquid and solid materials are separated by centrifugal action and in which the charge is continuously delivered and the solid matter intermittently discharged.

The main object of the invention is to secure a large capacity for the charge to be dried whereby the raw material may be delivered to the apparatus at a substantially constant rate.

A further object is to provide means whereby the size of the charge may be varied through a comparatively wide range without interruption of the operation of the apparatus in order to secure a fixed degree of dehydration even though the water content of the charge be variable.

A further object of the invention is to so design the parts that the solid matter to be dried is subjected to the minimum agitation so as to avoid unintentional breaking up or pulverizing of the solid material.

These and other objects may be secured by means of the apparatus disclosed in the accompanying drawings and which illustrate only two of various forms which my invention may assume.

In these drawings:

30 Fig. 1 is a central longitudinal vertical section of one form of my improved apparatus, the upper part of the drum being shown in discharge position, while the lower half is shown in the normal or main operating position,

35 Fig. 2 is a similar view of a second form, here again the upper half being shown in discharge position and the lower half in normal or operating position, said section being taken on the line 2-2 of Fig. 3, and

40 Fig. 3 is a vertical transverse section, the upper half being on the line X-Y and the lower half being on the line U-W of Fig. 2.

The apparatus illustrated in Fig. 1 includes a constantly rotating drum sieve A having a separate axially movable end wall B serving as a distributing member. This end wall is connected by piston rods 10 to a plurality of pistons or to an annular piston 11 mounted to reciprocate in corresponding

cylinders or cylinder 12 secured to the main drive shaft C. The fluid for actuating the piston in opposite directions at will may be delivered through passages in the shaft substantially as shown in my prior Patent 55 1,160,635, issued Nov. 16, 1915 and therefore need not here be described.

The material is fed to the drum by means of a suitable feed device D from a hopper S and through a conduit or chute H.

60 The axially movable end wall B includes a pair of annular spaced walls E₁ and E₂ which are rigidly connected together by braces R. The wall E₁ is imperforate and secured to the piston rods and substantially closely fits the drive shaft C. Its outer edge is spaced from the drum sieve A so as to permit the passage of material therebetween. The outer wall E₂ is also of annular shape, but is spaced from the shaft C to leave an opening 65 through which the conduit H extends and at its outer edge it closely engages the drum sieve A. The body portion of the wall E₁ is preferably substantially in a radial plane while the wall E₂ is conical so as to form an 70 annular funnel shaped space F between the two walls and into which the material is delivered and from which it passes at the narrowed periphery to the drum sieve A. The wall E₂ is of such a character that liquid 75 but not the solid material may pass therethrough and the chute H extends through the central aperture of the wall to such an extent that the material will be delivered into the space F irrespective of the axial position of this wall E₂.

80 In operation the funnel shaped space F is substantially filled with the material to be dehydrated and the walls E₁ and E₂ are in the position illustrated at the lower half of 85 Fig. 1 and the drum and all of the parts within the drum sieve are rapidly rotated. There is a preliminary dehydration of the material in the space F by the action of the sieve or perforated wall E₂ and the solid material collects at the outer narrow annular outlet of this space and crowds onto the drum sieve A where the final dehydration takes place.

90 The layer of material accumulating on the 100

drum sieve will be of a thickness indicated as K and which is dependent upon the distance between the periphery of the wall E₁ and the drum sieve. This distance may be chosen according to the quality and peculiarities of the material which is to be centrifuged.

The predetermined spacing of the wall E₁ and the drum sieve A may be varied at will 10 by placing one or more annular rings or extensions T on the periphery of the wall E₁.

If desired the apparatus may be provided with means whereby the solid material accumulating on the drum sieve may be 15 washed. As shown I provide an annular imperforate wall or drum a encircling the operating pistons and cylinders and rigidly connected thereto. This wall has inwardly directed flanges at its opposite end, the flange 20 at the outer end being wider than that at the inner end. A pipe c for washing liquid terminates adjacent the inner surface of the drum a and is distributed over the inner surface of this drum by the action of centrifugal force. Liquid may overflow the narrow 25 flange at the inner end and be thrown against the material on the drum sieve or the drum a may be provided with spray openings b through which the liquid is discharged by 30 centrifugal force.

All of the rotatable parts may be enclosed in a housing L which receives the liquid thrown out from the drum sieve A as well as that thrown from the screen wall E₂. This liquid may be collected at the bottom of the housing and discharged therefrom.

The sieve drum A at the end opposite to the distributing walls E₁, E₂ is provided with outlet openings G for the solid material. These may register with passages connected to or extending through the housing L. When the material which has accumulated on the inner surface of the drum sieve A has been dried to the desired extent, fluid may be admitted to actuate the piston and force the walls E₁, E₂ toward the left from the position shown at the bottom of Fig. 1 to the piston shown at the top of Fig. 1. This will force material along the surface 50 of the drum sieve where it will be thrown out by centrifugal force through the openings G. The walls may then be restored to normal position, the entire operation taking place without interfering with the continuous rotation 55 of the parts or the continuous delivery of material to the space F in which the predrying takes place.

The braces R which connect the walls E₁ and E₂ are in the form of vanes forming flues 60 therebetween so as to guide the material and to cause it to rotate with the drum and with the minimum amount of beating or breaking up.

The apparatus illustrated in Figs. 2 and 3 65 operates in substantially the same way as

that illustrated in Fig. 1, but differs therefrom in matters of design, details and arrangement of parts. Instead of having a plurality of pistons or an annular piston there is provided a single disc piston K' 70 which is connected to the center of the wall E₁. Instead of delivering the material through an inclined chute H I have provided a conduit H' which extends axially through the shaft and bearing so that the opening in the wall E₂ may be very materially smaller. The washing attachment is omitted from the form shown in Fig. 2 and in order to prevent premature discharge from the drum A and to prevent the material from falling away 75 from the drum in case the speed of the machine is reduced, there is provided an inner wall O for the chamber containing the material being dried. This wall is connected to the periphery of the wall E₁ and may have 80 an outwardly turned flange at its outer edge which may engage with the end of the drum sieve A to close the discharge port G as shown at the bottom of Fig. 2 or may move away 85 from said drum to open the port as shown at 90 the top of Fig. 2.

In operation the discharge movement of the distributing plate B and its walls E₁, E₂ may be performed as frequently as may be desired depending upon the character of 95 the material being treated. Each time it moves axially in one direction it pushes material along the drum and pushes a portion of the material beyond the drum so that it will be thrown out through the openings G. As the wall moves in the opposite direction 100 the space which it uncovers will be filled with further material moving out from the space F. This back and forth movement may be only at rare intervals as the pressure of the material in the space F may continuously 105 tend to slide the material along the drum A to the discharge ports or the distributing wall may be moved back and forth continuously. The length of the stroke of the reciprocating parts may be controlled if desired 110 by means of adjustable stops in the path of the movement of the actuating piston. In Fig. 2 I have shown such a space Q threaded 115 through the end wall of the cylinder. Similar stops may, of course, be used with the form shown in Fig. 1.

I have illustrated the device as mounted with its axis horizontal and this is preferably 120 the position, but it will be obvious that the same principle of operation might be employed in a device constructed with a vertical axis of rotation.

In the construction illustrated it will be 125 noted that the range of the distributing member which includes the walls E₁ and E₂ is very materially less than the effective length of the drum sieve. Therefore the material is pushed along the drum intermittently or step by step. The distributing member may 130

be operated continuously back and forth or may move comparatively rapidly through the two strokes and then remain for some time at the outer end, that is the position 5 shown at the bottom of Fig. 1. As the distributing member moves back from the position shown at the upper part of Fig. 1 to the position shown at the bottom of Fig. 1 centrifugal force will force out the material at the same rate to fill the space uncovered on the drum and to maintain a uniform thickness of material on the latter.

The size of the openings in the reticulated walls A and E₂ may depend upon the character 15 of the material being treated. They should be such that the liquid can pass through but the solid cannot.

The distributing member is, of course, rotated with the shaft by means of its connection 20 to the cylinder block, while the drum may be connected to the shaft in any suitable manner as for instance by an end wall P attached to the periphery of the cylinder as shown in Fig. 2 or the water chamber wall a 25 as shown in Fig. 1.

Having thus described my invention, what I claim as new and desire to secure by Letters Patent is:

1. A centrifugal machine having a reticulated 30 peripheral wall, a distributing member having annular axially spaced walls forming a chamber therebetween, the outer wall contacting with said peripheral wall and the inner wall being spaced therefrom, means for delivering material to be treated to said space, and means for effecting a relative axial movement of said peripheral wall and distributing member.

2. A centrifugal machine having a reticulated 40 peripheral wall, a distributing member having annular axially spaced walls forming a chamber therebetween, the outer wall contacting with said peripheral wall and the inner wall being spaced therefrom, means for continuously delivering material to be treated 45 to said space, and means for effecting a relative axial movement of said peripheral wall and distributing member.

3. A centrifugal machine including a drum 50 sieve having a discharge opening at one end thereof, a distributing member including a pair of walls axially spaced to provide a receiving chamber for the material to be treated, the outer wall being substantially conical 55 and having its periphery engaging said sieve and the inner wall having its periphery spaced from said sieve to a predetermined distance to control the thickness of the layer of material accumulating on said sieve, and 60 means for effecting a relative axial movement of said sieve and said member.

4. A centrifugal machine as defined in claim 3 in which a portion of the conical wall is reticulated to permit predrying of the material 65 between said walls.

5. A centrifugal machine having a peripheral wall, an annular, substantially conical end wall having its periphery engaging the peripheral wall and having an opening at its center through which the material to be dried is introduced, means for reciprocating said end wall, and a conduit projecting through said opening to a point beyond the limiting movement of said end wall. 70

6. A centrifugal machine including a reticulated peripheral wall, a distributing member including spaced annular walls, the outer edge of the outer wall engaging the peripheral wall and the outer edge of the inner wall being spaced from the peripheral wall, and means for varying the effective distance between said peripheral wall and the inner edge of the inner wall of said distributing member. 75

7. A centrifugal machine including a reticulated peripheral wall, a distributing member including spaced annular walls, the outer edge of the outer wall engaging the peripheral wall and the outer edge of the inner wall being spaced from the peripheral wall, 80 and a removable ring for varying the distance between the outer edge of said inner wall and said peripheral wall to control the thickness of the layer of material accumulating on the peripheral wall. 85

8. A centrifugal machine including a reticulated peripheral wall having a discharge outlet for solid material at one end, and a distributing member at the other end, said distributing member including a pair of spaced annular walls, the outer edge of the outer wall engaging said peripheral wall and the inner edge of the inner wall being spaced from said peripheral wall, means for effecting relative longitudinal movement of said distributing member and said peripheral wall, and an annular wall within said peripheral wall and spaced therefrom and secured to the inner wall of said distributing member, said annular wall having means for opening and closing said discharge outlet by said relative longitudinal movement. 100

Signed at Munich, Germany, this 27th day of January, A. D. 1930.
